[57] **CLAIM**

The ornamental design for an auxiliary handle, as shown and described.

DESCRIPTION

FIG. 1 is a bottom perspective view of an auxiliary handle showing our new design, a bag being held by the auxiliary handle being shown in broken lines as environmental structure only and forming no part of the claimed design;

FIG. 2 is a front elevational view thereof, the rear being a mirror image thereof;

FIG. 3 is a top plan view thereof; and,

FIG. 4 is a left side elevational view thereof, the right side being a mirror image thereof.

FIG. 1

FIG. 2

FIG. 3

FIG. 4
